[57] ABSTRACT

The description discloses a crane which has an apparatus for dampening swinging motion of a load. This is accomplished by means, mounted to the crane, for allowing motion of the load in two separate planes and means for braking the movement of the load within each of said planes. The load may be restrained for movement in one plane by rotatably connecting the lifting end of the crane boom about the longitudinal axis of the boom and the load may be restrained within the other plane by pivotally connected a cable restraining means to said lifting end of the boom. Selective braking action to the load within the planes dampens its swinging movement.

CRANE ATTACHMENT FOR DAMPENING SWINGING MOTION

The present invention relates to a crane attachment for dampening swinging motion of a load, and particularly to an apparatus which attaches to a lifting cable crane for selectively dampening the swinging motion of a load being carried by the crane.

Problems have always existed with regard to the operation of a lifting cable crane in that a load suspended from the crane has a tendency to go through random swinging motions due to external forces acting on the crane and the load. Such swinging motions can occur whether the crane be on land or at sea. A land based crane is highly susceptible to strong winds which may cause the load which is being raised or lowered to start swinging. A rocking of the crane base caused by a shifting of the ground underneath the crane may also cause a swinging motion in the load, and load swinging motion may be introduced by the mere operation of the crane as it moves the load from one location to another. The load swinging motion becomes even more acute when the crane is located aboard a ship which is constantly subjected to wave actions. Not only do wave actions effect the ship and, therefore, the crane but also strong winds may combine to make sea loading or unloading a particularly hazardous undertaking. Such undertakings are hazardous to both property as well as personnel since on land and on board a ship building structures are almost always in close proximity to the crane. In addition, there are usually a number of workers in the vicinity of the crane including those whose job it is to attach or detach the load from the crane, observers and related personnel.

Special problems exist when the crane is used to carry out scientific experiments at sea since it is quite common for a crane to be used to move a heavy instrument package from the deck of a ship into the water and then drag the package in the water for a certain period of time. While the sea might have been calm when the heavy package was originally placed in the water at the beginning of the experiment, it often happens that upon conclusion of the experiment the sea has roughened considerably. Therefore, the job of raising the heavy load out of the water and replacing it back on board the ship becomes a very complicated and highly dangerous job, for not only is the ship's crew in danger from the swinging load but also the ship itself because the momentum gained by a heavy swinging load can be considerable and has been known to buckle ship plating.

Two additional problems caused by a swinging load are: an adverse effect on cable life expectancy and excessive bending moments upon the crane. The more the load is allowed to swing the greater are the stresses and strains put upon the cable and the crane. By reducing or eliminating the swinging motion a particular size crane will have an increased capacity for lifting and lowering and cable life can be extended.

The present invention has solved all of the above mentioned problems by its ability to selectively dampen the swinging motion of a load which is either being raised or lowered; therefore, danger to personnel is greatly reduced, danger to property is reduced, and cable life and crane capacity are extended. In a preferred embodiment of the invention the problems are solved by combining with a lifting cable crane an appa-

ratus comprising a stiff connector connected at one end to the lifting cable and at the other end to the load, retainer means for coacting with the stiff connector, means for pivotally connecting the retainer means to the crane for engaging the stiff connector to dampen swinging motion of the load and for disengaging the stiff connector so that the load is free from said retainer means, braking means, means for connecting the braking means to the crane, means including the retainer means for connecting the braking means to the load when the stiff connector is engaged with the retainer means, said braking means for braking pivotal movement of the retainer means so that a swinging motion of the load is retarded when the stiff connector and the retainer means are engaged.

It is pointed out that while a preferred embodiment comprises the braking means, the stiff connector and the retainer means in combination, dampening may also be achieved with just a braking means or with just the combination of a stiff connector and retainer means apparatus. While each of the above embodiments is able to dampen swinging motions to a certain extent the preferred embodiment combination, as shown in the drawings, is a more effective and efficient dampening apparatus.

Reiterating, the advantages of the present invention are threefold: (1) the potential danger to personnel and property is greatly reduced or eliminated; (2) cable life expectancy is greatly extended; and (3) crane lifting capacity is greatly increased. While all of the above advantages are achieved, the apparatus has not resulted in any new disadvantages.

An object of the present invention is to provide an apparatus for a lifting cable crane which will allow the crane to raise and lower heavy objects without danger to personnel and property from a swinging motion of the load, said apparatus being able to selectively, easily, and efficiently dampen the swinging motion of the load.

Another object of the present invention is to provide an apparatus for a lifting cable crane which will extend cable life.

A further object of the present invention is to provide an apparatus for a lifting cable crane which will enable the crane to achieve a greater lifting capacity.

Still another object of the present invention is to achieve all of the foregoing advantages with a simply constructed and easily operable apparatus which is attachable to a lifting cable crane.

Other objects, advantages and novel features of the invention will become apparent from the following detailed description of the invention when considered in conjunction with the accompanying drawings wherein:

FIG. 1 shows an ocean going vessel and a lifting cable crane which utilizes the present invention to dampen swinging motion of the load in a rough sea;

FIG. 2 is a partially cut away side view of a preferred embodiment of the invention mounted at the end of the crane;

FIG. 3 shows a front view of the embodiment as seen from the right side of FIG. 2;

FIG. 4 is a plan section view of two locking chops taken on the plane IV—IV of FIG. 3 looking in the direction of the arrows.

Referring now to the drawings, wherein like reference numerals designate like or corresponding parts throughout the several views, there is shown in FIG. 1 a seagoing vessel 10 with an "articulated" crane 12 lo-

cated near the stern end of the vessel. An articulated crane is one that has a jointed crane boom 16, the joint for this crane being at 14. The use of a joint enables far more flexibility than can be achieved with just a straight one piece boom. The actual location of the preferred embodiment of the invention is at the lifting end 18 of the crane so as to be in close proximity to the load 20. In normal use an articulated crane operates by being able to move at its center joint 14 as well as at pivot 22, to allow the crane end 18 a considerable degree of freedom. Therefore, the heavy load 20 when on deck 24 may be attached to the crane then raised, moved over the side and lowered adjacent the water all without the necessity of unreeling the cable. In the particular application shown in FIG. 1 the heavy load 20 may be a scientific instrument package which is intended to be lowered into the water and then dragged at a desired depth below the ship for a certain period of time or for a certain distance. The articulated crane is able to lower the load almost to the level of the water before it becomes necessary to unreel the cable. Likewise when retrieving the heavy load the crane 12 may be lowered as close to the water as is possible and then the cable is rewound.

The main difficulties encountered when operating an articulated crane or, for that matter, any crane aboard a moving vessel 10 is that there is a great deal of rolling and pitching motion occasioned by rough seas and/or high winds. The rough seas act upon the ship in three ways, the first being a pitching motion whereby the ship will be moved about an axis transverse to the ship so that the bow will be alternately raised and lowered by the waves. The second set of motions will be rolling, which is motion around the longitudinal (bow to stern) axis. And the third set of motions is about a vertical axis as the ship is propelled through the water. When these three sets of motions are put together the reference plane of the crane becomes extremely mobile. The forces set up by the motions of the ship are transmitted to the crane 12 and then to the load 20 causing the load to have a tendency to swing haphazardly. It is the undesirable swinging motion of the load 20 that the present invention retards or eliminates. It should also be noted that a ground crane is also subjected to forces which tend to move its reference plane such as soft or shifting ground, or the momentum built up by merely moving a heavy object. The crane is also subjected to the possibility of high winds even though it be upon solid ground. Therefore, the present invention apparatus is adaptable to cranes, articulated or otherwise, under conditions where the crane may be on a seagoing vessel or at some stationary location upon land.

The preferred embodiment of the present invention is shown in more detail in FIGS. 2 and 3. As mentioned earlier, the invention may be attached at the end 18 of the crane. The preferred invention is allowed two degrees of motion, that is, the apparatus has the ability to rotate in two different planes. The first plane may be considered to be coincident with the surface of the drawing in FIG. 3 with rotation occurring about an axis located at 26. When the load is attached this rotational motion will allow the load to rotate laterally with respect to the crane. The second degree of rotation occurs about an axis 28, FIG. 2, which allows rotation in the plane of drawing as shown in FIG. 2. Superimposing the two degrees of rotational motion allows a relatively free degree of movement by the load 20. Thus, each

axis permitting the above rotation serves as a gimbal permitting movement by the load 20.

When the articulated crane is placing the load into the water the crane is near one of its fully extended positions so that there will be rotation about the axis 28 until the load is almost linear extension of the end of the crane. If there is movement of the ship at the same time then there will be a rotation of the apparatus about axis 26 also. During retrieval of the load 20 the apparatus will be rotated as just described until the load is pulled out of the water at which point the dragging force of the water against the load will no longer be present to dampen swinging motion. If the vessel 10 is rolling or pitching to any great degree the forces will then act upon the load 20 causing it to start its swinging motion.

The dampening apparatus comprises braking means which may include two braking units 30 and 32, FIG. 2, and means for connecting the braking means to the crane such as shroud 34 which may be welded to an inner hollow shaft 36 received therein. The hollow shaft 36 is rotatably mounted within and supported by a housing 38 intermediate the ends of the boom 16, the housing being mounted to the boom in any suitable manner such as by having upwardly extending welded ears 40 and 42 which are bolted to the boom as shown in FIG. 2. A means for connecting the braking means to the load which may comprise two supporting channel means 44 and 46, FIG. 3, between which cable or painter 48 may pass. The preferred apparatus also comprises a stiff connector 50, FIG. 2, which is connected at its upper end to the cable 48 and at its opposite end to the load 20. The stiff connector 50 may be of a generally cylindrical shape with an eyelet 52 for receiving cable 48 and a slot with two bolts 99 and 100 at its lower end adapted so that it may be securely attached by bolts to the load 20. The apparatus is further comprised of a retainer means or load adaptor 54, FIG. 3, which may be of a cylindrical tube design so as to receive the stiff connector 50, and means for pivotally connecting the retainer means 54 to the lifting end of the boom 18, which may include the two channel elements 44 and 46 which are in turn pivotally supported by the shroud 34.

All of the apparatus except for the housing 38 and part of the first brake unit 30 is rotatable about the axis 26 in the plane of the drawing of FIG. 3. The elements that rotate about axis 28 in the second plane, that is the plane of the drawing in FIG. 2, are part of the second brake unit 32, the two supporting channel means 44 and 46, the retainer means 54, and the load 20. Therefore, it is this last group of elements which are adapted to be rotatable about both of the planes of motion already mentioned. The preferred embodiment is completed by having holding means which may be locking chops 58 and 60, FIG. 4, pivotally connected to the retainer means 54 and in turn the supporting channel means 44 and 46. The locking chops are adapted to engage the stiff connector 50 in one position (solid lines of FIG. 4) and disengage the stiff connector in another position (phantom lines of FIG. 4).

While the preferred embodiment includes all the elements listed above, an apparatus including only several of the elements in combination may also give improvement in the control of swinging motion of the load. Hence, an apparatus which does not have the second brake unit, the stiff connector, or the retainer means

but only the first brake unit 30, may provide an improvement in load swing control. The rotation about axis 26 may be controlled by the first brake unit 30 which may be comprised of a rotatable element such as an outer drum 62 which is mounted on the hollow shaft 36 and rotatable therewith, and a stationary element 64 which may be mounted on housing 38 and comprised of several segmented inflatable bladders of a friction material. The bladders may be hydraulically inflated through hose 66 causing the bladder 64 to expand and engage rotatable element 62 for effective braking. This braking motion would tend to retard the swinging motion of the load about axis 26 which is the axis of rotation of the hollow shaft 36 as it rotates within housing 38. The housing 38 may contain a sleeve bearing 68 for receiving the shaft 36. It should be noted that a major advantage is gained by having rotation about axis 26 when axis 26 is coincident with the longitudinal axis of the cable 48, as it passes through shaft 36; for to have such causes the least amount of stresses and strains on the cable due to rotational motion. If the longitudinal axis of the cable is not coincident with the axis 26 then there will be a certain degree of twisting and distorting of the cable 48 causing rapid wear and resulting in shortened cable life.

An apparatus which comprises only the stiff connector 50, the retainer means 54 and means for connecting the retainer means to the crane would also offer an improvement in controlling the swinging motion of the load. The swinging motion may be controlled by having the retainer means coact with the stiff connector, such as by engagement. The means connecting the retainer means to the crane enables the stiff connector and retainer means to engage to dampen swinging motion and to disengage so that the load is free from the retainer means. In the engaged position the stiff connector 50 may be adapted to fit snugly within the retainer means 54. By preventing rotation about axis 28 and having a snug engagement between the stiff connector and the retainer means, swinging motion is damped. This snug arrangement would also prevent the cable 48 from leaving the groove of the sheave 56. The main advantage is that the cable is better protected and has less stress and strain upon it. Therefore cable life is extended while at the same time the swinging motion of the load 20 is restricted.

When an apparatus includes the first and second braking units 30 and 32 in addition to the stiff connector 50, the retainer means 54 and the means for connecting the retainer means to the crane, not only is the cable life extended but more effective control is achieved over the rotation motion about axis 28. Brake 32 may be comprised of a stationary element, such as clamps 70, and a movable element, such as discs 72. Each of the clamps 70 may be a pair of friction discs (not shown) which are oppositely disposed within a housing (seen in FIG. 2) and inwardly driven to make engagement with opposite sides of a respective disc 72 by hydraulic pressure through lines 74. These clamps have the trade name of "Calipers" and may be purchased from Goodyear Corporation. The clamps 70 may be connected to a frame assembly 71 which in turn is welded to the shroud 34. The clamps 79 are accordingly stationary relative to rotational movement about the axis 28 but are rotatable about axis 26 since the shroud 34 is connected to and is rotatable with the movable drum 62 of the first brake unit. Each of the

discs 72 may be connected to a respective channel support 44 or 46 by a bolted-on hub 73 which receives the shaft at 28 and is in turn rigidly connected to the channel support by any suitable means such as welding. The two channel supports 44 and 46 form a relatively rigid connection with the load 20 by way of the stiff connector 50 and the retainer means 54. An operator selectively applying hydraulic pressure through the hoses 74 may be selectively retard the disc 72. Thus the advantages achieved by the apparatus having the two brake units and the snug engagement of the stiff connector and the retainer means provides retardation of the swinging motion in two planes, one perpendicular to the other, as well as providing extended cable life by keeping the cable aligned within the groove of the sheave 56 and by causing rotation about an axis coincident with the axis cable 48.

By adding the last major feature, that is the locking chops 58 and 60, to an apparatus containing the two brake units, the stiff connector and the retainer means, the complete preferred embodiment is created. The locking chops are actuated by a tubular hydraulic actuator 80 which receives two oppositely spaced shafts 76 and 78 which may be selectively actuated by hydraulic fluid flowing through hose 82 into the actuator between the shaft ends. The locking chops 58 and 60 are pivotally connected at 82 and 84 to chop guides 86, 88, 90 and 92 which are located in pairs above and below each of the locking chops so that the chops may pivot from a disengaged position (shown in phantom lines in FIG. 4) to an engaged position (shown in solid lines in FIG. 4) with the stiff connector. The chop guides 86, 88, 90 and 92 are in turn rigidly connected to the channels 44 and 46 by any suitable means such as welding. An annular depression 96 may be placed in the stiff connector 50 so that when the stiff connector is in a snug position within the retainer means 54 the locking chops extend through opposite slots in the retainer and engage the annular depression 96 and support the stiff connector 50 as shown in FIG. 2. The main advantage of having the locking chops is that when in the engaged locking position the weight of the load 20 is no longer carried by the cable 48 but is transferred through the locking chops to the channel supports 44 and 46 and thence back to the crane end 18. As explained earlier, since an articulated crane has the ability to retain the load close to the crane end 18 during much of the movement of the heavy load, a considerable extension of cable life can be achieved as the cable is not carrying any of the load. Also the entire apparatus becomes relatively rigid since the stiff connector may be blocked at one end by the locking chops and at the other end by an annular positioning block 98 which locates the stiff connector in the proper position for the locking chops to engage. Thus, the relatively rigid formation enables the brake units 30 and 32 to more effectively operate to retard the swinging motion of the load because all of the swinging motion will take place about the two axes 26 and 28.

OPERATION

Operation of the inventive apparatus is extremely simple, effective and efficient. The articulated crane 12 is able to move about its pivot points 14 and 22 to bring its end 18 in close proximity to a load 20 upon the deck 24 of a vessel 10. The load may then be attached as shown in FIG. 2 to the stiff connector 50 by any conve-

nient method such as the bolts at 99 and 100. By having locking chops 58 and 60 in their engaged position with the stiff connector 50 so that a relatively stiff connection is achieved between the load and the crane, the weight of the load 20 is carried by the locking chops 58 and 60 rather than the cable 48. The crane may then lift the load off the deck 24 and move it over the side of the ship and then down to the crane's lower limit which should place the weight 20 just above the water level. It is during this time when the weight 20 is being moved from the deck to the water level that a swinging motion of the weight may occur in the two planar directions mentioned earlier. The operator by selectively feeding hydraulic fluid into hoses 66 and 74 may cause the brake units 30 and 32 to retard the swinging motions in their respective planes. Once the crane has reached its lower limit the locking chops are moved into their disengaged position by relieving the hydraulic fluid from line 82 causing the actuator shafts 76 and 78 to retract within the actuator 80 thereby pivoting the locking chops. The load then becomes suspended by the cable and is lowered into the water to the desired depth. It should be noted that at no time does the load have extreme swinging motions which cause the jerking and severe stress and strain in the cable 48 or the severe bending moment forces on the crane 12. Thus, the cable life is extended and the crane is able to lift larger weight loads. The actuator shafts 76 and 78 may be retracted by a spring within the actuator 80.

Once the weight is at the desired depth there will be little or no excessive swinging motions as the drag of the water tends to stabilize the load. When the experiment is finished the crane is again lowered to its limit just above the water line and the cable is reeled in until the stiff connector 50 abuts the annular positioning block 98. The operator may then feed hydraulic fluid through line 82 to actuate the locking chops 58 and 60 to their engaging and locking position with regard to the annular depression 96 of the stiff connector 50. Once again, the weight of the load is removed from the cable 48 and is taken up by the locking chops and transmitted back to the crane. The load 20 is then lifted back aboard the ship while the operator selectively activates the brake units 30 and 32 to prevent excessive swinging motions. Thus, not only can the entire operation be done in considerably more safety, but the entire operation may be done far more efficiently and in considerably less time with considerably less chance of failure of the crane or the cable.

Obviously many modifications and variations of the present invention are possible in the light of the above teachings. It is therefore to be understood that within the scope of the appended claims the invention may be practiced otherwise than as specifically described.

I claim:

1. In combination with a lifting cable crane, apparatus to substantially dampen swinging motion of a load suspended from the cable comprising:

a stiff connector connected at one end to the lifting cable and at an opposite end to the load;
retainer means for restrainably engaging said stiff connector;

means pivotally connecting the retainer means to the crane;
braking means;
means for connecting the braking means to the crane; and

means including the retainer means for connecting the braking means to the load when the stiff connector is engaged with the retainer means,
said braking means for braking pivotal movement of the retainer means so that swinging motion of the load is retarded when the stiff connector and the retainer are engaged.

2. An apparatus as claimed in claim 1 wherein the braking means comprises:

a first brake unit; and
a second brake unit,

the second brake unit being disposed in a perpendicular relationship to the first brake unit,
whereby the first brake unit retards swinging motion in a first plane and the second brake unit retards swinging motion in a second plane perpendicular to the first plane.

3. An apparatus as claimed in claim 1 wherein the stiff connector comprises:

a generally cylindrical member;
said retainer means being adapted to receive said cylindrical member.

4. An apparatus as claimed in claim 1 wherein the retainer means comprises:

a cylindrical tube disposed about the lifting cable and adapted to snugly receive the stiff connector when engaged therewith.

5. An apparatus as claimed in claim 1 wherein the retainer means comprises:

a cylindrical tube disposed about the lifting cable and adapted to snugly receive the stiff connector when engaged therewith; and
holding means connected to the crane for engaging the stiff connector and supporting the load when the connector is received within the retainer means so that the weight of the load is transferred from the lifting cable to the crane.

6. An apparatus as claimed in claim 5 wherein:
the stiff connector is a generally cylindrical member;
the cylindrical member being adapted to fit snugly within the cylindrical tube;

the holding means comprises pivotally connected locking chops adapted to pivot from a disengaging to an engaging position with respect to the cylindrical stiff connector;

the cylindrical stiff connector having an annular depression for receiving the locking chops; and including

an annular block connected within the cylindrical tube for positioning the stiff connector to receive the locking chops within said annular depression.

7. An apparatus as claimed in claim 1 wherein:

a cylindrical housing is mounted to the crane;
a hollow shaft is rotatably mounted and supported within the housing and adapted to receive the cable therethrough;

a first brake unit having a stationary element and a rotatable element is supported by the housing, the stationary element being attached to the housing, the rotatable element being attached to the rotatable shaft and being rotatable in a plane perpendicular to the axis of the shaft;

a second brake unit having a stationary element relative to the rotatable element of the first brake unit and a rotatable element, said rotatable element of the second brake unit being rotatable in a plane

perpendicular to the plane of rotation of the rotatable element of the first brake unit;
 shroud means rotatable with the rotatable element of the first brake unit for connecting said stationary element of the second brake unit to the rotatable element of the first brake unit;
 a sheave means rotatably connected to said shroud means for receiving the cable and aligning the cable along the longitudinal axis of the hollow shaft;
 the retainer means comprises a cylindrical tube disposed about a section of cable between the load and the sheave means;
 channel means for pivotally supporting and connecting the tube to the rotatable element of the second 15
 brake unit; and
 locking chops pivotally connected to the channel means and adapted to pivot from a disengaging to an engaging position with respect to the stiff connector,
 the stiff connector being a generally cylindrical member having an annular depression for receiving the locking chops,
 whereby the locking chops support the load by engaging the annular depression of the stiff connector. 25

8. In combination with a crane which has a swinging boom and a sheave mounted at the lifting end of the boom, apparatus for dampening swinging motion of a load suspended from a cable over said sheave comprising:

rotatable means including brake means located intermediate the ends of the boom for rotatably connecting the lifting end of the boom and the sheave about the longitudinal axis of the boom;
 cable restraining means pivotally connected to the lifting end of the boom for restraining movement of the load within the plane of the sheave; and
 means connected to the boom for selectively braking

10
 pivotal movement of the cable restraining means, whereby swinging motion of the load can be selectively damped in two planes of movement.

9. In a crane having a boom and means for elevating the boom, the improvement comprising:
 a. a jib pivotally connected to the boom;
 b. means connected to the jib for pivotally raising and lowering same with respect to the boom;
 c. a gimbal connected to the jib;
 d. a load adapter mounted upon said gimbal, said load adapter including means for guiding a painter, and
 e. controllable braking means for constraining the movement of said load adapter with respect to said jib.

10. The improvement in a crane as defined in claim 9 wherein the gimbal is a two-axis gimbal and wherein said controllable braking means are separately controllable on each of the axes.

11. In a crane having a boom and means for elevating the boom, the improvements comprising:
 a. a jib having a proximal end and a distal end, the proximal end being pivotally attached to the boom;
 b. means connected to the jib for pivotally raising and lowering the distal end thereof with respect to the boom;
 c. a gimbaled load adapter connected to the distal end of said jib, said load adapter including means for guiding a painter, and
 d. controllable braking means for constraining the movement of said load adapter with respect to said jib.

12. In a crane having a boom and means for elevating the boom, the improvement comprising a gimbaled load adapter, said load adapter including means for guiding a painter, and controllable braking means for constraining the movement of said load adapter.
